UNITED STATES PATENT OFFICE.

WILLIAM HOCHHAUSEN, OF NEW YORK, N. Y.

SHORT-CIRCUITING SWITCH FOR DYNAMO-ELECTRIC MACHINES.

SPECIFICATION forming part of Letters Patent No. 252,663, dated, January 24, 1882.

Application filed November 7, 1881. (No model.)

To all whom it may concern:

Be it known that I, WILLIAM HOCHHAUSEN, of the city, county, and State of New York, have invented certain new and useful Improvements in Switch Apparatus for Dynamo-Electric Machines, of which the following is a specification.

The object of my invention is to prevent the excessive spark which occurs when the current flowing from a dynamo-electric machine is suddenly interrupted.

It is a well-known fact that when the main or principal circuit of a dynamo-electric machine supplying one or several lights is suddenly broken an excessive spark occurs, this being due, as is generally understood, to what is known as the "extra current." This extra current, being of a high tension, often breaks through the insulation of the helices upon the machine and does serious damage, while the spark which occurs at the switch-points at the moment of disruption burns the switch.

The object of my invention is to prevent the extra current, so far as may be, and to protect the helices of the machine and the switch-points from injury. This I accomplish by forming a short circuit around the field-of-force magnets of the machine when the switch is turned for the purpose of cutting off the flow of current to the main circuit, the short circuit being formed before the main circuit is interrupted. By this means the field-of-force magnets are robbed of the current which energizes them, so as to materially decrease the strength of the current generated, while at the same time the current which would otherwise flow to line is also diverted into the short circuit. The short circuit, as above set forth, having been first formed, when the switch is turned farther to break the connection with the main line, but little if any extra current is apparent. My invention may be therefore said to consist in combining with a dynamo-electric machine a continuity-preserving switch adapted to break the connection of the machine with the main line, one of the points of said switch being connected to the main circuit, while its other point is connected to a branch adapted to form a short circuit around the field-of-force magnets of the machine.

Having now described the general principles

of my invention, I will proceed to describe one kind of apparatus that may be used for carrying the same into effect.

In the accompanying drawing I have shown 55 a diagram representing an old form of dynamo-electric machine connected to a main line containing several lights in circuit, and to a cut-off switch with circuit-connections made according to my invention.

A and B represent the field-of-force magnets of any dynamo-electric machine; a b, their curved pole-pieces; and gh, collector or commutator brushes applied to the surface of a commutator-cylinder, to which the coils of the armature rotating between the field-of-force poles are connected in any well-known manner. One of the commutator-brushes is connected, as is ordinarily the case, with one of the main-line binding-posts, 1, while the other brush is connected with the helices upon the field-of-force magnets, and through said helices with the other binding-post, 2. The main-line wires are represented by the figures 7 and 8, and are shown as including at P several electric lamps 75 in circuit. Switch-lever S is connected with binding-post 1, and the switch-point K for said lever with one of the main-line wires. The other switch-point L for the lever is connected to a loop or branch wire, 10, running from the 80 collector-brush g. The point of the switch-lever is split, as shown, or formed in other suitable manner, so as to preserve the contact in passing from one point to the other and to make full and prolonged contact with one 85 point before breaking contact with the other. The lever may be turned, as is well understood, to connect wholly with point K or with point L. When in contact with K the circuit is from collector-brush h of the armature, through the 90 switch-lever S, point K, main-circuit wire 7, lights at P, wire 8, field-of-force coils, collector-brush g, and through the coils of the armature to brush h, thus completing the circuit. Under these conditions the machine is feeding the circuit in the well-known manner, and the current generated in the armature-helices being carried through the field-of-force helices increases the strength of the field of force magnetism, which latter reacts upon the armature. If the 95 switch were turned so as to break the main circuit, no switch-point L being provided, there

would be a flash and spark between S and L, which would burn the contacts, while, moreover, the extra current to which the flash is due being of high tension would be liable to break through and destroy the insulation of the wires upon the field-of-force magnets. As, however, the switch is turned to first make contact with L and loop 10 before breaking the main-line connection, a short circuit is provided for the current from the armature-helices, the circuit being through h, 1, S, L, 10, and g, and as the field-of-force magnets are thus robbed of their energizing-current the strength of the current generated is simultaneously and immediately largely diminished. At the same time the current is also short-circuited from the line. When, now, the movement of the switch is completed so as to break the main-line connection at K, scarcely any spark will occur.

I do not limit myself to any particular construction of switch, as many forms of continuity-preserving switch may be employed in place thereof, provided the connections be so made that a short circuit for the field-of-force magnets is formed before the connection with the main line is broken. 25

What I claim as my invention is—

The combination, with a dynamo-electric machine, of a switch for making and breaking 30 the main-line connection with the machine, and circuit-connections to said switch, as described, whereby a short circuit around the field-of-force magnets is formed before the main-line connection is broken.

WILLIAM HOCHHAUSEN.
